UNITED STATES PATENT OFFICE.

JOHN A. WINTROATH, OF LOS ANGELES, CALIFORNIA, ASSIGNOR TO PEERLESS PUMP COMPANY, OF LOS ANGELES, CALIFORNIA, A CORPORATION OF CALIFORNIA.

DEEP-WELL TURBINE PUMP.

Application filed October 1, 1923. Serial No. 665,894.

To all whom it may concern:

Be it known that I, JOHN A. WINTROATH, a citizen of the United States, residing at Los Angeles, in the county of Los Angeles 5 and State of California, have invented a new and useful Deep-Well Turbine Pump, of which the following is a specification.

This invention relates to turbine pumps of the type employed for raising water 10 from deep wells.

For the purpose of raising water from deep wells, multi-staged turbine pumps are employed. The impellers of these pumps are ordinarily driven through a vertical 15 shaft which extends to the surface of the ground, and is surrounded by a tubular oil casing through which lubricating oil is delivered to bearings supported in the casing and in which the shaft turns.

20 The lower end of the oil column, in the standard form of turbine pump, is in communication with the water column of the pump, it being impractical to maintain a perfectly tight joint about the shaft at this 25 point. A certain amount of leakage of oil at this point does no harm, since the oil is carried upwardly with the water and discharged therewith, and the leakage is made evident by a lowering of the upper surface 30 of the oil level in the casing, which can be observed and compensated for by the addition of more oil. Any leakage of water into the casing through the bottom thereof is, however, a bad thing as this water 35 places the oil and seriously interferes with lubrication. If the leakage is gradual the oil may be replaced with water through a greater portion of the casing without the operator becoming aware of this fact.

40 It is an object of my invention to prevent water from entering the casing and displacing the oil therefrom, and this object I accomplish by subjecting the lower end of the oil column to a pressure considerably 45 lower than that produced by the pump.

One convenient method of accomplishing this is to provide in the pump a pressure relief chamber disposed around the drive shaft at a point adjacent to the uppermost 50 impeller, and to provide a communication between this pressure relief chamber and one of the lower pump stages, thus maintaining a pressure in the pressure relief chamber substantially lower than the pressure 55 produced by the pump. Since the

pressure relief chamber is interposed between the water column being lifted and the oil column, any leakage of water around the shaft from the water column passes into the pressure relief chamber and does not enter the oil column. Also since the oil column is balanced against the pressure in the pressure relief chamber, it is only necessary to maintain this pressure at a lower value than the natural static head of 60 the oil column. This I accomplish by directly connecting the pressure relief chamber into a portion of the pump in which such a low pressure is maintained.

The advantages of the invention and further objects thereof will be made evident hereinafter.

Referring to the drawing which is for illustrative purposes only,

Fig. 1 is an elevational view showing a 75 multi-stage turbine pump embodying the features of my invention.

Fig. 2 is an enlarged fragmentary vertical section illustrating in detail the features of the invention.

80 In Fig. 1 of the drawing, 11 indicates a three stage turbine pump situated in a well 12, and secured to the lower end of a water lift pipe 13. At the head of the well, a driving means such as a motor 14 is connected to an impeller drive shaft 15, which extends through a tubular casing 16. As shown particularly in Fig. 2, the turbine pump employs first, second and third stage bowls 17, 18 and 19, which are in the form 85 of housings, suitably secured together and having therein impellers 21, 22 and 23.

90 Water in the well entering the suction pipe 25, supported by a casting 26, is delivered by the uppermost impeller 23, which 95 delivers the water through the passage 30 into the pipe 13 at sufficient pressure to discharge the water at the mouth of the well. Each stage of the turbine pump imparts to the flow of water a designated amount of 100 pressure so that as the water is carried upwardly from stage to stage, the pressure thereof is increased to the pressure required to carry the water to the surface.

105 Let it be considered that each stage of the turbine pump is designed to deliver a 25-pound pressure to the water. Under these conditions, the pressure in the passage 28 of the lower stage bowl 17 would be 25 pounds per square inch; the pressure 110

in the passage 29, 50 pounds per square inch; and the pressure in the passage 30, 75 pounds per square inch. This pressure in the uppermost bowl 19 is above the static pressure of oil in the space 35 between the shaft 15 and the shaft casing 16.

The difference in pressure between the oil and water would, unless my invention was employed, result in the passage of the 10 water inwardly, as indicated by the arrow 38 in Fig. 2, between the impeller and the core 39 of the bowl 19, the water displacing the oil in the space 35. This, however, is prevented by the employment of a pressure 15 relief chamber 42 formed in the casting of the core 39 at a point immediately above the impeller 23. The pressure within the chamber 42 is maintained, at a value somewhat less than the static head of the oil, by 20 the employment of an equalizing pipe 44 which communicates between the pressure relief chamber 42 and the passage 28 of the lower bowl or housing 17, in which a pressure of 25 pounds per square inch is held 25 by the impeller 21. By this inter-communication the pressure within the pressure relief chamber 42 is held at the same pressure as the passage 28, namely 25 pounds per square inch, which is considerably lower 30 than the pressure of 75 pounds per square inch created in the passage 30 by the combined action of the impellers 21, 22 and 23. Any water which is forced between the impeller 23 and the core 39 and upwardly 35 will pass through small openings 47 in the bearing into the pressure relief chamber 42, from whence it is carried through piping 44 to the lower stage passage 28.

By the use of this arrangement, an ample 40 supply of oil may be at all times maintained in the bearings of the pump, owing to the fact that the water cannot rise within the oil column and cause the displacement thereof, thus eliminating the necessity of 45 frequently adjusting the packing member 48, Fig. 1, which must be done in the ordinary type of turbine pumps in order to prevent the forcing of the oil upward in the oil column by the water pressure at the 50 lower end thereof.

It will be immediately evident that by maintaining positive lubrication, the life of the pump bearings may be very materially increased. The arrangement herein shown produces this greatly desired result. 55

I claim as my invention:

1. In a turbine pump, the combination of: a plurality of stage housings; impellers in said stage housings; a shaft for driving said impellers; a tubular casing surrounding said shaft for supporting a column of lubricating oil; walls enclosing a pressure relief chamber around said shaft at a point adjacent to the uppermost of said impellers; and a tubular member communicating between said relief chamber and the fluid passage of one of said stage housings in which a pressure is existent during operation, substantially in balance with the static head of the lubricating oil column. 70

2. In a turbine pump, the combination of: an impeller housing; a bearing at the upper end of said housing; a shaft extending upwardly through said bearing to a driver; an oil tube extending upwardly from said housing and surrounding the shaft; an impeller on said shaft within said housing; and means for releasing the water collected at high pressure between the upper face of said impeller and the lower end of said bearing so as to prevent upward displacement of said oil by said water. 75

3. In a turbine pump, the combination of: a plurality of stage housings; impellers in said stage housings; a shaft for driving said impellers; a tubular casing surrounding said shaft for supporting a column of lubricating oil; bearing means at the upper end of said group of stage housings, said bearing receiving said shaft and being adjacent 90 to the column of lubricating oil; and means for releasing the water collected under pressure between the upper end of said impellers and the lower end of said bearing so as to prevent upward displacement of said oil by said water. 95

In testimony whereof, I have hereunto set my hand at Los Angeles, California, this 22d day of September, 1923.

JOHN A. WINTROATH.
